CLAIM

The ornamental design for a modular canopy shelter unit, as shown and described.

DESCRIPTION

FIG. 1 is a top perspective view of a modular canopy unit in accordance with a first embodiment of the present invention; FIG. 2 is a bottom perspective view of the modular canopy shelter unit of FIG. 1 rotated 180° with respect thereto;

FIG. 3 is a side elevational view of the modular canopy shelter unit of FIG. 1;

FIG. 4 is a side elevational view of the modular canopy shelter unit of FIG. 1;

FIG. 5 is a side elevational view of the modular canopy shelter unit of FIG. 1;

FIG. 6 is a side elevational view of the modular canopy shelter unit of FIG. 1;

FIG. 7 is a top plan view of the modular canopy shelter unit of FIG. 1;

FIG. 8 is a bottom plan view of the modular canopy shelter unit of FIG. 1 rotated 90° with respect to FIG. 7;

FIG. 9 is a top perspective view of a modular canopy shelter unit constructed in accordance with a second embodiment of the present invention;

FIG. 10 is a bottom perspective view of the modular canopy shelter unit of FIG. 9 rotated 180° with respect thereto;

FIG. 11 is a side elevational view of the modular canopy shelter unit of FIG. 9;

FIG. 12 is a side elevational view of the modular canopy shelter unit of FIG. 9;

FIG. 13 is a side elevational view of the modular canopy shelter unit of FIG. 9;

FIG. 14 is a side elevational view of the modular canopy shelter unit of FIG. 9;

FIG. 15 is a top plan view of the modular canopy shelter unit of FIG. 9; and,

FIG. 16 is a bottom plan view of the modular canopy shelter unit of FIG. 9 rotated 90° with respect to FIG. 15.
